ATTORNEY

UNITED STATES PATENT OFFICE.

JOHN F. MUNCEY, OF EVERETT, WASHINGTON.

ROTARY ENGINE.

SPECIFICATION forming part of Letters Patent No. 737,127, dated August 25, 1903.

Application filed January 19, 1903, Serial No. 139,509. (No model.)

To all whom it may concern:

Be it known that I, JOHN F. MUNCEY, a citizen of the United States, residing at Everett, in the county of Snohomish and State of Washington, have invented certain new and useful Improvements in Rotary Engines, of which the following is a specification, reference being had therein to the accompanying drawings.

- 10 This invention relates to improvements in rotary engines; and its object is to provide an engine of this class which will produce a maximum of power with a minimum consumption of steam. I attain this object by 15 providing improved facilities for automatically regulating the admission of steam in such manner as to obtain a high degree of efficiency, by the improved construction of a steam-balanced rotary driving-wheel, and by 20 the various other mechanical details of construction and combinations thereof, as will be hereinafter described and claimed, and illustrated in the accompanying drawings, in which—
- 25 Figure 1 is a vertical transverse section of a rotary engine embodying my improvements; and Fig. 2 is a longitudinal section of same, taken on line 2 2 of Fig. 1. Figs. 3 and 4 are perspective views, respectively, of 30 one of the steam-abutments and one of the valves shown in the other views.

In the said drawings the letter A denotes the engine shell or casing, provided with a cylindrical bore A'. B is a rotary wheel of less 35 diameter than the said bore and is mounted on a longitudinal shaft S, which is journaled in bearings s of the cylinder ends a and provided with suitable stuffing-boxes, such as a'. A plurality of wings or pistons C extend from 40 the periphery of the said wheel to the circumferential surface of the bore and are each formed with an inclined or tangential advance face c and a radial following face c'.

Steam inlet and exhaust ports D and E, respectively, are provided in the casing and arranged, preferably, so that each pair will be diametrically opposite—that is, an inlet and exhaust port on each side—thus equalizing as far as possible the steam-pressure upon 45 the wheel, and the friction is consequently reduced. The exhaust-ports lead directly from the cylinder and are always open. The

inlet-ports are connected to the cylinder by cylindrical - shaped valve - chambers F, in which are pivotally mounted the valves G and abutments H. The latter are each hinged central of the said chamber by trunnions h h', of which h' projects outside of the casing through stuffing-box h'' for making connection with a lever-arm I, carrying a counter-weight i, whereby the abutment is prevented from slamming against its bearing-seats M and at the same time can be adjusted to regulate the speed of its motion. The abutments extend, inclusive of the wiping-strips herein- 55 after mentioned, across the entire diameter of the valve-chambers to peripheral surface of the wheel, while the said bearing-seats extend, preferably, from near the axes of said chamber to the wheel circumference. The 60 valves G are severally provided with a bent shank g, which extends through an aperture k of an abutment and terminates in an end g', projecting internally of the cylinder to be within the path of the aforesaid revoluble 65 pistons. Said aperture of the abutment is ground to make a steam-tight fit with bossed enlargement k' of the valve-shank, which is pivotally connected to the abutment by pin l eccentric of the valve-chamber and the axis 70 of said trunnions.

Suitable packing, such as rings P, are seated in annular grooves in the wheel ends, and at the wiping ends of the pistons, valves, and abutments are strips N, T-shaped in cross-section and having their webs inserted in slots O, in which preferably are springs acting to force the packing - strips to press against their respective wiping-surfaces.

The operation of the invention will now be 85 described, reference being had to Fig. 1, wherein one of the steam-inlet ports is shown closed and the other open. The steam enters the cylinder through the said open port and acting between the adjacent abutment 90 and piston drives the latter until the said valve is closed by the following piston to rotate the wheel in the direction indicated by the arrow y. The revolving pistons severally engaging the shank ends of the valves 95 100 to move the same to close the inlet-ports and the said ends moving forwardly with the actuating-piston carry the inner ends of the abutments into pockets T, provided so as to

permit the pistons passing thereby. Immediately a valve-shank is released by the engaged piston the steam-pressure on the face of the valve unseats the same by reason of 5 the valve being hinged eccentric of the chamber or to one side of its axis, when the steam is admitted freely and accelerates the seating of the abutment.

What I claim as new, and desire to secure 10 by Letters Patent, is—

1. In a rotary engine, the case A having cylindrical valve-chambers F, inlet-ports D, exhaust-passages E and the rotary wheel B provided with pistons C, in combination with 15 valve G provided with a bent shank g projecting in the path of said pistons, said shanks being fulcrumed eccentric of the valve-chamber, substantially as set forth.

2. In a rotary engine, the combination of 20 T-shaped packing-pieces N with the pistons C, oscillating abutment H and the oscillating valve G, and the case A and the wheel B, substantially as set forth.

3. In a rotary engine, the oscillating abutment H hinged on trunnions h h' intermediate its length and projecting into wiping contact with the periphery of wheel B, and 25 its pistons C, the arm I and counterweight i,

in combination with the case A, and the wheel B, substantially as set forth.

4. In a rotary engine, the oscillating abutment H, having an aperture k in combination with the valve G having a shank extended through said aperture and pivotal connection between the said abutment and the valve-shank, substantially as set forth. 35

5. In a rotary engine, the combination with the case A, of the wheel B having pistons C upon the periphery thereof, cylindrical valve-chamber F, steam-inlet D opening in said 40 chambers, abutments H fulcrumed concentric of said valve-chambers and having their ends normally in wiping contact with the wheel and cylindrical walls of the valve-chambers, the valves G provided with shanks 45 g extending through said abutments and terminating in the path of said pistons, said valves being fulcrumed eccentric of said valve-chambers, substantially as set forth.

In testimony whereof I affix my signature 50 in presence of two witnesses.

JOHN F. MUNCEY.
